UNITED STATES PATENT OFFICE.

WILLIAM B. FRENCH, OF CHARLESTOWN, MASSACHUSETTS.

DESIGN FOR A BOOK-MARK.

Specification forming part of Design No. 1,074, dated December 14, 1858.

To all whom it may concern:

Be it known that I, WILLIAM B. FRENCH, of Charlestown, in the county of Middlesex and State of Massachusetts, have invented or produced a new and original Design for a Book-Mark; and I hereby declare that the said new design is fully described and represented in the following description and accompanying drawings, to which reference is hereinafter made.

The figures of the accompanying plate of drawings represent my improvements. Figure 1 is a front elevation of a book-mark. Fig. 2 is a central longitudinal section taken in the plane of the line A B.

My new design for a book-mark consists of

a hand attached to and placed within a heart. *a a* in the drawings represent the heart, ornamented with small stars *b b* and raised moldings *c c*. The center of the heart is cut away and the space occupied by a hand pointing.

Having thus described my new design, what I claim as my invention or production, and desire to have secured to me by Letters Patent, is—

The new design for a book-mark, consisting of the hand placed within the heart, as described, and represented in the drawings.

WILLIAM B. FRENCH.
